CLAIM

We claim the ornamental design for a French press mixer, as shown and described.

DESCRIPTION

FIG. 1 is a bottom perspective view of a French press mixer, showing our new design;

FIG. 2 is a top perspective thereof;

FIG. 3 is a side view thereof;

FIG. 4 is a bottom view thereof; and,

FIG. 5 is a perspective view thereof in a condition of use. The invention is round and uniform.

The broken lines in the drawings depict portions and structural environment of the French press mixer that form no part of the claimed design.
